UNITED STATES PATENT OFFICE

135,068

DESIGN FOR A JACK CLAMP

Richard F. Smith, Savannah, Ga., assignor to
Welding Tools & Engineering Corp, Atlanta,
Ga.

Application November 16, 1942, Serial No. 108,788

Term of patent 14 years

To all whom it may concern:

Be it known that I, Richard F. Smith, a citizen of the United States, residing at Savannah, in the county of Chatham and State of Georgia, have invented a new, original, and ornamental Design for a Jack Clamp, of which the following is a specification, reference being had to the accompanying drawing, forming part thereof.

Fig. 1 is a side elevational view of a jack clamp, showing my new design;

Fig. 2 is a top plan view;
Fig. 3 is an end elevational view; and
Fig. 4 is a side perspective view.

I claim:
The ornamental design for a jack clamp, as shown.

RICHARD F. SMITH.
